UNITED STATES PATENT OFFICE.

PHILIP B. HARRISON, OF CHICAGO, ILLINOIS, ASSIGNOR TO CHICAGO RAILWAY EQUIPMENT COMPANY, OF CHICAGO, ILLINOIS, A CORPORATION OF ILLINOIS.

REVERSIBLE STRUT FOR BRAKE-BEAMS.

1,105,138.

Specification of Letters Patent. Patented July 28, 1914.

Application filed November 16, 1911. Serial No. 660,742.

To all whom it may concern:

Be it known that I, PHILIP B. HARRISON, a citizen of the United States, residing at Chicago, county of Cook, and State of Illinois, have invented a certain new and useful Improvement in Reversible Struts for Brake-Beams, of which the following is a full, clear, and exact description, such as will enable others skilled in the art to which it appertains to make and use the same, reference being had to the accompanying drawings, forming part of this specification, in which—

Figure 1 is a plan view of a brake beam showing my improved strut in position thereon for use in connection with a right hand brake lever. Fig. 2 is a similar view showing my improved strut lever in position to be used in connection with a left hand 20 brake lever. Fig. 3 is a top plan view partly in section of my improved reversible strut. Fig. 4 is a side elevational view of the same. Fig. 5 is an end elevational view of the same. Fig. 6 is a cross sectional view 25 through the stem of the strut.

This invention relates to a new and useful improvement in reversible struts especially adapted for use in connection with brake beams, the object being to construct a strut 30 whose ends are substantially alike and provided with seats for the compression and tension beam members respectively, whereby the strut is interchangeable end for end and may be used for either a right or left 35 hand brake lever for inside and outside hung brakes.

My invention also contemplates means for fixedly securing the strut upon the compression member, which means is practically 40 duplicated at each end of the strut, and incidentally to this securing means, I also provide each end of the strut with a perforated projection which may be employed as an element of the third suspension or support 45 such as disclosed in the Kiesel patent, No. 997,922, dated July 11th, 1911.

By the use of my invention it is possible for the makers of brake beams and their 50 customers, such as railroads who wish to carry repair parts in their shops, to dispense with right and left hand struts, the manufacturers economizing in the manufacture of these struts by the use of a single pattern where two patterns have heretofore been re-

quired for right and left hand one piece struts.

In the drawings: 1 indicates the compression member shown here as U-shaped in cross section, although it is obvious that compression members of different cross sectional contour may be employed; 2 is the tension member here shown as a round rod, although it is obvious that other forms of tension members may be employed; 3 is the strut, said strut being shown as having a single pin hole at the center thereof.

B is the slot through which the brake lever passes, said slot preferably not extending throughout the length of the cylindrical portion of the strut, but terminating short of the ends thereof, so as to provide solid cylindrical end portions integral with the strut ends.

C are the end walls of the strut from which extend a wall D for embracing the compression member, this wall D having perforated lugs E at diagonally opposite corners of the strut for the attachment of 75 brake release springs and third suspension members, the latter being indicated at 4 in Fig. 4.

F indicates seats for the tension member arranged at each end of the strut and within the wall D. The compression member 1 is arranged within its seat provided by the wall D and afterward a wedge 5 is driven through an opening substantially parallel to the end wall C, so as to engage the legs of the compression member and force the same outwardly against the wall D. The 90 small end of the wedge key is bent down by the blow of a hammer to prevent the same from being accidentally displaced.

The walls of the shank portion of the strut are preferably reinforced by interior 95 strengthening ribs G and exterior strengthening ribs H forming substantially a cruciform shape, which adds materially to the strength of the strut as a column.

In operation, the upwardly presented lugs 100 E over the compression member may be employed for the attachment of a third suspension hanger, while the downwardly presented lugs E at the diagonally opposite corner of the strut may be employed for the 105 attachment of the block 4 which co-operates with the third suspension spring. In service, if it is desired at any time to reverse

the position of the strut, it is turned end for end, and any wear which might have occurred in the pin opening and which is indicated by dotted lines *a* in Fig. 4, will be taken up by the changed position of the strut and the unworn wall *b* of the pin opening will now be located in front of the pin to receive the strain.

Claims:

13. 1. A reversible strut having seats for the compression and tension members at each end and provided with transversely disposed key openings for the reception of wedge keys whereby the compression member is clamped in position.
14. 2. A one piece reversible strut having a solid wall at each end forming a seat for the compression member, seats for the ten-

sion member located within said solid wall and wedge key openings for receiving wedge 20 keys which coöperate with the legs of the compression member.

3. A reversible strut having solid walls at each end forming seats for the compression member, seats for the tension member 25 located within said walls and wedge key openings traversing the compression member seats.

In testimony whereof I hereunto affix my signature in the presence of two witnesses, 30 this 13th day of November, 1911.

PHILIP B. HARRISON.
